United States Patent

Des. 240,624
Patented July 20, 1976

240,624

PORTABLE WATER PURIFIER

Harry Grant MacMurray, 900 NE. 45th St., Apt. 74,
Pompano Beach, Fla. 33064

Filed May 10, 1974, Ser. No. 468,823

Term of patent 3½ years

Int. Cl. D23—01

U.S. Cl. D23—3

FIG. 3.

FIG. 2.

FIG. 1.

FIG. 1 is a front elevational view of a portable water purifier showing my new design;

FIG. 2 is a side elevational view thereof; and

FIG. 3 is a top plan view thereof.

The fragmentary broken line representation of a water container in FIGS. 1 and 2 is for purposes of illustration only.

I claim:

The ornamental design for a portable water purifier, as shown and described.
